UNITED STATES PATENT OFFICE

149,384

DESIGN FOR A LUMINOUS PLANT CONTAINER OR THE LIKE

Victor Sherry and Harry A. Plocky, Los Angeles,
and Gustave F. Plocky, South Pasadena, Calif.

Application June 24, 1946, Serial No. 130,992

Term of patent 7 years

(Cl. D35—3)

To all whom it may concern:

Be it known that we, Victor Sherry and Harry A. Plocky, citizens of the United States and residents of the city of Los Angeles, in the county of Los Angeles and State of California, and Gustave F. Plocky, a citizen of the United States and resident of the city of South Pasadena, in the county of Los Angeles and State of California, have invented a new, original, and ornamental Design for a Luminous Plant Container or the like, of which the following is a specification, reference being had to the accompanying drawings, forming part thereof, in which:

Fig. 1 is a perspective view of a luminous plant container or the like showing our new design;

Fig. 2 is a top view thereof;

Fig. 3 is a side view thereof; and

Fig. 4 is a cross-sectional view taken along the line 4—4 of Fig. 3.

We claim:

The ornamental design for a luminous plant container or the like, as shown.

VICTOR SHERRY.

HARRY A. PLOCKY.

GUSTAVE F. PLOCKY.
